CLAIM

The ornamental design for a cap for a liquid container, as shown and described.

DESCRIPTION

FIG. 1 is a top view in perspective of a cap for a liquid container showing my new design;
FIG. 2 is a front view thereof;
FIG. 3 is a rear view thereof;
FIG. 4 is a top view thereof;
FIG. 5 is a bottom view thereof;
FIG. 6 is a first side view thereof; and,
FIG. 7 is a second side view thereof.

(Continued)

The dashed lines shown in the drawings illustrate portions of the cap that are not claimed and form no part of the claimed design. The dash-dot lines represent the boundary of the claimed design.

1 Claim, 5 Drawing Sheets
